UNITED STATES PATENT OFFICE.

ANSON W. HALL, OF JOHNSTOWN, PENNSYLVANIA.

LAMP.

No. 909,785.

Specification of Letters Patent.

Patented Jan. 12, 1909

Application filed April 4, 1908. Serial No. 425,246.

To all whom it may concern:

Be it known that I, ANSON W. HALL, a citizen of the United States, residing at Johnstown, in the county of Cambria and State of Pennsylvania, have invented new and useful Improvements in Lamps, of which the following is a specification.

This invention relates to improvements in lamps, and particularly safety lamps for the use of miners, the object of the invention being to provide a novel construction of locking means for securing the oil font or pot of the lamp to the body of the lamp in such manner as to prevent removal of the font except by an authorized person provided with a proper type of key.

The invention consists of the features of construction, combination and arrangement of parts hereinafter fully described and claimed, reference being had to the accompanying drawing, in which:—

Figure 1 is a side elevation of a commercial type of miner's safety lamp embodying my invention. Fig. 2 is an elevation, partially in section, of the lower portion of the lamp body and the font. Fig. 3 is a detail view of the locking dog. Fig. 4 is a similar view of the key.

Referring to the drawing, the numeral 1 designates the base of the body of the lamp, on which the burner is mounted in the ordinary or any preferred manner, which base is provided with a depending internally threaded flange 2, the lower edge of which is formed at one point in its circumference with a keeper socket or recess 3 having at one end a straight or abrupt locking shoulder 4 and provided with a beveled or inclined upper wall 5 leading therefrom to the basal surface of the flange.

The oil font or pot 6 is formed at its upper end with an externally threaded flange 7 for engagement with the threads of the flange 2, by which said font is adapted to be secured in position at the lower end of the body of the lamp to form the base of the complete lamp. The flange 7 is of reduced diameter with respect to the vertical wall of the font and is connected therewith by an inturned annular horizontal ledge or shoulder 8, which is formed with a slot 9 substantially coextensive in length with the locking recess 3. Below said slot 9 the vertical wall of the font 6 is provided with a chamber 10 having at one side of its center a horizontal shoulder 11 and at the opposite

side of its center a depending recess or enlargement 12. Fixed to the inner wall of said chamber adjacent the upper end of said recess is a guard pin 13, which projects into and is exposed through a keyhole 14 in the outer wall of the chamber, said keyhole being of approximately circular form and having a substantially U-shaped base or extension 15.

A locking dog 16, comprising an elongated metallic strip, is arranged within the chamber 10 and mounted to swing vertically upon a pivot pin 17, the pivoting point being closer to one end of the dog than to its opposite end, thus eccentrically mounting the dog to provide a locking arm 18 and operating arm 19 of unequal lengths. A substantially V-shaped leaf spring 20 is disposed in the chamber 10 between the shoulder 11 and arm 18 of the dog, one leaf of said spring bearing on said shoulder and the other on said arm, thus normally projecting the arm 18 upward through the slot 9, while the arm 19 is held depressed within the chamber immediately above the guard pin 13. A key 25 is provided for retracting the dog and is formed with a stem having a socket or recess 21 at its outer end to receive and engage the pin 13, thus allowing said key to be inserted into the portion 12 of the chamber, and also with a bit 22 of proper form to fit the portion 15 of the keyhole. The short end or arm 19 of the dog is provided with a depending projection 19^a to prevent the bit of the key from slipping off the end of said arm, and wedging between the same and adjacent wall of the recess.

In the operation of applying the filled font, the flange 7 is screwed within the flange 2 of the base of the lamp in the ordinary way until the ledge 7 bears against the lower face of said flange 2, the arm 18 of the dog being held against the resistance of the spring down into the chamber 10 by the pressure of the bottom face of the flange 2 until said dog comes into alinement with the recess 3, at which time the arm 18 will be projected by the spring into said recess and held therein so that the end of said arm will bear against the shoulder 4. By this means the font will be locked against retrograde rotation in its fully applied position, so that it cannot be removed, except through the retraction of the dog by the use of a proper form of key, such as that shown. It will be understood that the inclined wall

5 of the recess 3 will permit the font to be turned a little further around for the purpose of tightening the threaded connection between the flanges when they become 5 slightly loosened from wear, but that any attempt to remove the font by reverse rotation will result in the engagement of the dog with the shoulder 4, whereby such attempt would be defeated. In order to release the dog for the removal of the font, the key is applied in an obvious manner and turned so as to bring its bit 22 into contact with the underside of the arm 19, whereupon the dog will be swung to a horizontal position, thus retracting the arm 18 and permitting the font to be screwed off.

The invention will be found of value to prevent the removal of the fonts of lamps by unauthorized persons, or by any one other 20 than a fire-boss or other authorized person provided with the proper type of key, thus obviating the danger of the ignition and explosion of gases in the mine from careless removal of the font and exposure of the 25 lamp flame. Unless the miner is provided with a key, he cannot remove the font, and yet the construction of the lock is such as to enable it to be removed for filling or other purposes by an authorized official, without 30 the necessity of the miner traveling a considerable distance to a station, as is necessary where complicated locks which can only be opened by the use of magnets or complicated mechanism are employed.

35 Having thus fully described the invention, what is claimed as new is:—

1. In a lock for lamps, the combination of a lamp body having a threaded base provided in the underside thereof with a recess 40 having an abrupt shoulder and an inclined wall, a lamp font provided with a coöperating threaded portion and formed with a horizontal chamber opening through its upper edge, said chamber being provided at 45 one side of its center with a horizontal shoulder and at the opposite side of its center

with a depending recess or enlargement, the latter having a keyhole leading thereto, a dog comprising a bar eccentrically pivoted within said chamber and having a locking 5 arm located above the shoulder in said chamber and an operating arm located above said recess, a spring disposed between said shoulder and the locking arm to tilt the dog and project said locking arm for engagement 55 with said recess and shoulder upon the lamp base, and a key guide within said recess or enlargement and in alinement with the key-hole.

2. In a lock for lamps, the combination of 60 a lamp body having a threaded base provided in the underside thereof with a recess having an abrupt shoulder and an inclined wall, a lamp font provided with a coöperating threaded portion and formed with a 65 horizontal chamber opening through its upper edge, said chamber being provided at one side of its center with a horizontal shoulder and at the opposite side of its center with a depending recess or enlargement, the 70 latter having a keyhole leading thereto, a dog comprising a bar eccentrically pivoted within said chamber and having a locking arm located above the shoulder in said chamber and an operating arm located above said recess, a spring disposed between said shoulder and the locking arm to tilt the dog and project said locking arm for engagement 75 with said recess and shoulder upon the lamp base, a key guide within said recess or enlargement and in alinement with the key-hole, and a depending lip or projection upon the operating arm of the dog arranged to co-operate with said guide and the bit of the key.

80 In testimony whereof I affix my signature in presence of two witnesses.
